METHOD OF DISTILLING PETROLEUM
UNDER VACUUM

Stephen S. Johnson, Jr., Short Hills, N. J., assignor to The M. W. Kellogg Company, New York, N. Y., a corporation of Delaware

Application November 20, 1930, Serial No. 496,885

5 Claims. (Cl. 196--77)

My invention relates to the distillation of oil and in particular to vacuum distillation of reduced stocks.

In previous vacuum distillation operations it has been the common practice to facilitate the distillation of heavy oils by the use of steam. By this means, it has been possible to obtain overhead cuts of heavy oils which otherwise are not obtainable. However, in using steam it has been necessary to use large sized fractionating towers and other equipment and also a vacuum equipment of large capacity in order to take care of the immense increase in vapor volumes because of the steam. Not only has it been necessary to increase the size and amount of the equipment with a resulting increase in expense, but it has also been necessary to increase the amount of cooling water and power used.

In order to obtain proper fractionation it is, of course necessary to have a suitable reflux in the upper portion of the tower. Previously in vacuum distillation processes reflux has been added or returned which is substantially of the same characteristics as condensate from the vapors passing from the top of the tower. This returned reflux is vaporized in the tower and further increases the total volume of vapor. This tends to decrease the fractionating efficiency of the tower and necessitates larger equipment to handle the vapors.

My process consists in removing the lighter products in a preliminary distillation under a vacuum without the use of steam. I then fractionate under a high vacuum, the bottoms from the first separation. In this second operation I may use some steam.

One of the primary objects of my invention is to overcome and eliminate the disadvantages outlined above.

A further object of my invention is to provide a method for vacuum distillation which does not necessitate excessively expensive or special equipment.

Another object of my invention is to obtain a vacuum distillation process for reduced stocks in which at least a portion of the distillation may be carried on without the use of steam.

Another object is to provide a process in which an increased percentage of heavy stock may be taken off overhead.

Another object is to provide a process by which a more complete fractionation and separation of the oil is provided.

Other objects and advantages of my invention will become apparent from the following descrip-

tion and drawing in which I have shown a diagrammatic outline of an apparatus which is suitable for carrying out my process.

Referring more particularly to the drawing in which like reference characters denote like parts, the feed stock is drawn from a source of supply through line 1 by the charging pump 2 and is forced through the line 3 into the pre-heater or heat exchanger 4, from which it passes into the line 5 through the heat exchanger 6 and 10 the line 7 into the heating tubes 8 and 8' inclosed in the refractory housing 9. The heated products pass from the pipe still through the line 10 into the fractionating tower 11. This portion of the fractionating tower extends down to the dividing 15 section 12 which separates the upper part of the tower from the lower part. The upper fractionating tower 11 is fitted with fractionating sections or plates 13 having preferably, bellcap and downflow equipment, not shown. Vapors 20 from the top of the tower pass off through the line 14 into the feed heat exchanger and partial condenser 4 and then through the line 15 into the total condenser 16. A cooling medium such as water may be admitted to the condenser 16 25 through the line 17 and discharged through the line 18. The liquid condensate is drawn off from the condenser through the line 19 and may pass into the accumulator 20 from which it may be drawn off by means of a pump 21 and forced 30 through the line 22 to storage. Fixed gases and other uncondensed material are drawn off from the condenser 16 through line 23 by means of the steam ejector 24. Superheated steam is passed into the ejector through the line 25. The 35 products are discharged from the ejector through the line 26 into the barometric condenser 27 to which cooling water is admitted through the line 28 and the condensed products and cooling water 40 withdrawn through the line 29. Vapors are withdrawn through the line 30 by the ejector 31 to which superheated steam is admitted through the line 32. The discharged products pass through the line 45 33 to the barometric condenser 34 to which cooling water is admitted through the line 35 and from which the condensed products and cooling water are discharged through the line 36. The vapor remaining in the barometric condenser 34 50 is withdrawn through the line 37 by means of the ejector 38 into which steam is admitted through the line 39. The products from this ejector may be discharged through the line 40 to a steam well, not shown. Other suitable appa- 55

ratus for maintaining a dry vacuum may be used of course, such as a dry vacuum pump.

Reflux condensate from the condenser 16 may be returned to the top of the tower 11 through the line 41 and pump 42. This line is controlled by the valve 43. Reflux from an outside source may also be charged to the top of the tower through the line 41', controlled by the valve 43'.

Liquid products may be withdrawn from several plates in the tower by means of the lines 44 and 45, and discharged to a stripping column 46 which may be fitted with stripping sections or plates 47 having preferably bellcap and downflow equipment, not shown. Vapors from this stripping tower pass through the line 48 controlled by the valve 49 into the vapor line 14. They may also be discharged into the line 50 controlled by the valve 51 and thence into a condenser and heat exchanger 52 which is a unit of a secondary vacuum system which will be described more fully later. Steam may be admitted to the stripping tower 46 through the line 53. The liquid products from the stripping tower are withdrawn through the line 54 and pass through the heat exchanger 6 to the cooler 55 from which they may be withdrawn by the pump 56 and passed to storage. Cooling liquid may be admitted to the cooler through line 55' and withdrawn through 55''. Additional stripping drums may be used to withdraw other side streams if desired.

The bottoms from the first flash in the fractionating tower 11 are withdrawn through the line 57 and forced by means of the pump 58, through the heating tubes 59 in the pipe still 8. The reheated products pass through the line 60 back into the lower fractionating tower 61. As has previously been described, this lower tower is separated from the upper fractionating tower 11 by means of the dividing section 12. This tower is fitted at its lower portion with stripping sections or plates 62 having preferably the usual bellcap and downflow equipment, not shown. The upper part of the tower is fitted with baffle plates 63. Steam may be admitted to the bottom of the tower through the line 64. The bottoms separated in this section are withdrawn through the line 65, through the cooler 66 and forced by means of the pump 67 to storage. Vapors from the fractionating tower 61 pass through the line 68 into the condenser and heat exchanger 52 to which cooling water is admitted through the line 69 and discharged through the line 70. Condensate in this condenser may be returned to the upper fractionating tower 11 by means of the pump 71 through the line 71'. Vapors are withdrawn from the condenser and heat exchanger 52 through line 72 by means of the steam ejector 73 to which preferably superheated steam is admitted through the line 74 and the products discharged through the line 75 to the barometric condenser 76. Condensing water is admitted to this barometric condenser through the line 77 and the liquid products are discharged through the line 78. The remaining vapors are withdrawn through the line 79 by means of the steam ejector 80 to which steam is admitted through the line 81 and the products discharged through the line 82 into a barometric condenser 83. A condensing liquid is admitted to this barometric condenser through the line 84 and the products discharged through the line 85. The remaining vapors are withdrawn through the line 86 by means of the steam ejector 87 to which steam is admitted through the line 88 and the products discharged through the line 89 to a steam well,

not shown. As stated before, any suitable type of equipment may be used to produce the desired vacuum.

The operation of my process is substantially as follows:

The charging stock, for example, reduced crude or other reduced stock is drawn into the system through the line 1 by means of the charging pump 2 and forced through the line 3 into the pre-heater 4 in which it obtains a preliminary heat 10 from the vapors being discharged from the top of the tower. The partially preheated stock is then forced through the line 5 into the exchanger 6 in which it picks up more heat from the lubricating oil cut being withdrawn from the tower. 15 The preheated stock which has been heated, for example, to a temperature of 400° F., then passes through the line 7 into the heating coils 8 and 8' of the pipe still. The feed stock is heated in the pipe stills up to a temperature, for example, of 20 650° to 700° F., and is discharged through the line 10 into the upper fractionating tower 11 where it is flashed at an absolute pressure of between 30 and 40 millimeters. The vapors pass upwards through the fractionating plates 13 where the 25 heavier portions are condensed and the vapors withdrawn through the line 14 to the condenser 4 where a partial condensation takes place due to the cooling action of the feed charging stock. The vapors and condensate then pass to the 30 total condenser 16 where further condensation takes place. The condensate is withdrawn through the line 19 and may pass to the accumulator 20 from which it is withdrawn by the pump 21 and forced to storage. This condensate under 35 ordinary conditions would be primarily gas oil and similar light fractions. Fixed gases and other vapors are withdrawn from the condenser 16 through line 23 by means of the steam ejector, barometric condenser and two stage ejectors with 40 interbarometric condenser system previously described. The products from the last ejector 38 are discharged through the line 40 to the atmosphere or if it is desired they may be discharged into a well.

Reflux from the condenser 16 may be returned to the top of the tower 11 through the line 41 by means of the pump 42. If it is desired reflux may be drawn from some outside source and admitted to the system through the line 41'. Liquid products such as, for example, wax distillate or light cylinder stock may be withdrawn from the plates 13 of the fractionating tower 11 through the lines 44 and 45. It is preferable that this withdrawn product be further fractionated to 55 strip it of any remaining light product and for this reason it is discharged into a stripping tower 46 in which further fractionation takes place. If it is desired to facilitate the stripping action, steam may be admitted to the stripping tower 60 through the line 53. The vapors pass off from the stripping tower through the line 48 and may be discharged into the vacuum system connected to the fractionating tower 11. These vapors may be discharged into the vacuum system connected 65 to the fractionating tower 61. No steam has been used in the first flash which takes place in the fractionating tower 11 and thus the vacuum system connected to the tower operates on what is commonly known as a dry vacuum. As will be 70 later described the vacuum system connected to the tower 61 operates on a wet vacuum. The vapors from the stripping tower therefore may be discharged either to the wet or dry vacuum system depending upon whether steam is used in 75

the stripping tower or not. The liquid products are drawn off from the stripping tower by means of the line 54 and give up a portion of their heat in the heat exchanger 6 to the incoming feed. They are then further cooled in the cooler 55 and forced by the pump 56 to storage.

The bottoms from the first flash in the fractionating tower 11 in which the light ends for example, gas oil, wax distillate and light cylinder stock have been removed, are withdrawn through the line 57 by means of the pump 58. The temperature of the stock withdrawn from the bottom of the fractionating tower 11 will be approximately 600-650° F. and is reheated to a temperature of substantially 750° F., in the heating tubes 59 in the pipe still. The reheated stock is then discharged into the lower fractionating tower 61 where it is flashed at a high vacuum, for example, 5-10 millimeters absolute pressure. The vapors pass upwardly around the baffle plate 63 and are withdrawn through the line 68 to the condenser 52. The condensate may be taken back through the line 16 into the upper fractionating tower 11. The vapors are withdrawn by means of the booster 25 ejector 13, the two stage ejectors 80 and 81 and the interbarometric condenser 83. The final vapors, fixed gases and steam may be discharged into a hot well.

The lower fractionating tower 61 is fitted with stripping plates 62 which thoroughly strip the liquid portion of the second flash. This stripping may be facilitated by the ejection of steam, through the line 64. The use of steam, of course, increases the volume of vapor, but due to the fact that the light ends have already been removed in the first flash and thus the vapor volume greatly reduced, it is possible to obtain an exceedingly high vacuum and a fine separation with less than the usual amount of steam. The products remaining liquid are withdrawn through the line 65 and the cooler 66 by means of the pump 67 and pass to storage.

The condensate formed from the vapors in the condenser 52 may be returned through the line 11 to the upper fractionating tower 11. This condensate of course, is of a lower gravity than the reflux condensate which would be returned to the tower from the condenser 16. At the temperatures present in the upper part of the tower 11, the low gravity condensate will vaporize much less than the reflux from the condenser 16 and thus would not tend to increase the vapor volumes to an undesirable degree. The heavy condensate would act as a cooling medium within the tower and form reflux condensate therein, making it unnecessary to return a proportional amount of reflux condensate from the condenser 16. This, of course, is decidedly advantageous inasmuch as it diminishes the vapor volumes within the tower and permits smaller and less expensive fractionating and vacuum equipment.

Inasmuch as prior to the second flash in the tower 61 the lighter ends have been removed, it is unnecessary to provide the usual bellcap plate equipment in the upper section of the lower tower and I am therefore enabled to do away with equipment which would tend to build up a back pressure and thus diminish the effectiveness of the high vacuum in the lower sections of the second fractionating tower 61. As I have shown in the drawing, I have merely inserted the baffles 63 in the upper part of the second fractionating tower. These serve to knock out liquid which is entrained in the vapors passing into the line 68, and yet do not sufficiently constrict the flow so

that there is a back pressure formed. In my process by using a dry vacuum in a first flashing operation I am able to obtain a relatively high vacuum and yet use a fractionating tower of comparatively small diameter and a vacuum forming equipment which is also of relatively small size. Furthermore, I am able to eliminate the expense of steam in the tower to facilitate distillation. Also due to the smaller vapor volumes I am able to materially cut down the amount of power, steam and cooling water necessary to effectively carry on my vacuum producing operation. Due to the fact that I have already removed the light ends, I am enabled to obtain a very high vacuum in the second flash with a relatively small quantity of vapors to handle, and thus again I have materially reduced the size of fractionating equipment and vacuum equipment necessary to carry out the fractionation process.

In a great many cases it is possible to have the first fractionating tower and the second fractionating tower of the same diameter so that they may be placed one above the other as I have shown in my drawing. This, of course, adds to the compactness of the unit and further decreases the expense of construction and operation.

As I have already described above it is possible to considerably reduce the amount of light reflux returned to the top of the tower 11 from the condenser 16 due to the fact that I may return the relatively heavy condensate from vapors from the second flash to the upper part of the fractionating tower 11 in which the first flash has taken place. This heavy condensate produces a large proportion of the necessary reflux within the tower as it passes downwardly through the plates 13 to the lower plates where it may be withdrawn through the lines 44 and 45 to the stripping column or through the line 57 to the reheater 59. I have thus been able to considerably reduce the vapor volume in the upper portion of the tower, and have therefore, overcome a difficulty which has been common in prior vacuum distillation equipment, namely, the tendency for excessive vapor velocities in the upper portion of the flashing tower with a resulting reduction in the fractionating efficiency of the tower and furthermore, a tendency for the vapors to carry with them a considerable amount of entrained liquid to the condensing and vacuum producing equipment.

The distillate which is withdrawn through the pipes 44 and 45 to the stripping column 46 may be further separated and fractionated in this column by the use of steam so that all light ends are removed. It can be seen therefore, that notwithstanding the fact that I use a dry vacuum in the first flashing operation I am still enabled to obtain a secondary close separation of the desired product by means of the steam and without the use of separate processing equipment. As I have described above, the vapors from this stripping column may be discharged to either the wet or dry equipment depending on whether it is necessary to use steam or not and other factors. By connecting the stripping column to the vacuum system for the second flash it may be possible to use a higher vacuum on the stripping tower and thus less steam would be required.

While I have shown and described only a specific process and form of apparatus, it is apparent to those skilled in the art that there are many modifications that may be made without departing from the spirit of the invention. I, therefore, do not wish to be limited by the apparatus and

process described in the specification and drawing, but only by the appended claims.

What I claim is:

5 1. The method of distilling oil which comprises heating the oil, separating the heated oil into liquid and vapor and fractionating the resulting vapor under a low absolute pressure without steam, withdrawing the liquid residue from said separating step and reheating it, and separating said reheated liquid residue into liquid and vapor with the assistance of steam under a lower absolute pressure than said first separation.

10 2. The method of distilling oil which comprises heating the oil, separating the heated oil into liquid and vapor and fractionating the resulting vapor under a low absolute pressure without steam, withdrawing the liquid residue from said separating step and reheating it, separating said reheated liquid residue into liquid and vapor with the assistance of steam under a lower absolute pressure than said first separation, subjecting the liquid condensate formed in the first fractionating to a stripping operation under vacuum with steam, and condensing the vapor from said stripping operation with the vapor from said second separation.

15 3. The method of separating lubricating oils from a topped crude oil which comprises heating the oil to an elevated temperature, passing the oil into a fractionating column, fractionating it therein while maintaining a substantial dry vacuum to produce lubricating oil fractions of intermediate boiling range and a heavy unvaporized fraction, withdrawing the latter and subjecting it without intermediate loss of heat to a further distillation under vacuum with the as-

sistance of steam whereby heavier lubricating oil distillates of higher viscosity are obtained.

4. The method of separating lubricating oil from a topped crude oil which comprises subjecting the oil to successive steps each of which comprises heating the oil while rapidly flowing in a confined stream through a heating zone, imparting to the oil in that zone substantially all the heat needed for vaporization, discharging the heated oil into a separating chamber maintained 10 under vacuum and separating the oil into a vapor and a residue; in one of said steps rectifying the vapor under a substantial dry vacuum to produce a rectified lubricating oil distillate of intermediate boiling range and viscosity; and in the 15 succeeding step passing the heated oil countercurrent to a current of steam to vaporize lubricating oil of higher boiling range and viscosity.

5. The method of separating lubricating oil from a topped crude oil which comprises heating 20 the oil while rapidly flowing in a confined stream through a heating zone, imparting to the oil in that zone substantially all the heat needed for vaporization, discharging the heated oil into a separating chamber maintained under vacuum 25 and separating it into a vapor and a residue, rectifying the vapor under a substantial dry vacuum to produce a lubricating oil distillate of intermediate boiling range and viscosity and a heavy unvaporized fraction, withdrawing the latter and 30 subjecting it without intermediate substantial loss of heat to a further distillation under vacuum with the assistance of steam whereby a heavier lubricating oil distillate of higher boiling range and viscosity is obtained.

35 STEPHEN S. JOHNSON, JR.
